UNITED STATES PATENT OFFICE.

ROLF THELEN, OF MADISON, WISCONSIN; DEDICATED, BY MESNE ASSIGNMENTS, TO
THE PEOPLE OF THE UNITED STATES.

REVERSIBLE CIRCULATION INTERNAL FAN KILN.

Original application filed April 19, 1924, Serial No. 708,323. Divided and this application filed March 7, 1925. Serial No. 14,423.

(GRANTED UNDER THE ACT OF MARCH 3, 1883; 22 STAT. L. 625.)

To all whom it may concern:

Be it known that I, ROLF THELEN, a citizen of the United States of America, and an employee of the Department of Agriculture, 5 residing in Madison, Wisconsin (whose post-office address is Forest Products Laboratory, Madison, Wisconsin), have invented a new and Improved Reversible Circulation Internal Fan Kiln.

10 This application is a division of an application filed April 19, 1924, which bears Serial Number 708,323.

This application is made under the act of March 3, 1883, Chapter 143 (22 Stat. 15 625), and the invention herein described and claimed may be used by the Government of the United States, its officers and employees, and by any person in the United States without the payment to me of any royalty thereon. 20 I hereby dedicate the same to the free use of the Government and the people of the United States.

My invention consists in an improvement in the design of forced circulation kilns or 25 chambers for drying and conditioning lumber or similar material. However, its use is not limited to wood or wood products. It consists in the adaptation of fans of the disk type, or similar types, to the production of 30 a unique internal circulation of air and the vapor in the kiln combined with the production and regulation of the heat and the humidity within the kiln.

This invention is illustrated in Figures 1 35 to 3. Figure 1 represents a cross-sectional elevation. Figure 2 represents a horizontal section partly above and partly below the rails. Figure 3 represents a longitudinal sectional elevation taken approximately 40 through the center of the kiln.

The principal feature which I claim as 45 novel and an improvement over existing kilns is the use and arrangement of the fans and the air distributing system. This arrangement is such that a very fast and uniform circulation of air and vapor through the piles of lumber may be secured and it permits the periodic reversal of the direction 50 of the air movement by simply reversing the direction of rotation of the fans. The air distributing system provides a very uniform flow of air throughout the length

and breadth of the kiln and eliminates the non-uniformity of drying, which is one of the commonest troubles experienced in the ordinary kiln. The arrangement of the fans upon a series of cross shafts provides a simple means of producing a brisk circulation; and the elimination of comparatively small ducts such as those used in external 60 blower kilns reduces very materially the work required to produce a given circulation. The differences in air pressure required in the operation of this kiln are much smaller than those ordinarily required in 65 kilns employing centrifugal blowers, and the disk fans operate very efficiently at these low pressures. Measurements recently made indicate that the static pressures necessary for the successful operation of this system 70 are materially less than one-eighth of an inch of water pressure. It is possible, therefore, by the use of this invention to produce a very great and uniform circulation of air and vapor within the kiln with a very small 75 expenditure of power.

While it is obvious that there are many possible ways in which the use of internal fans can be adapted to dry kilns of different types, this invention is limited to double 80 track kilns in which the lumber is edge stacked. In edge stacked lumber the width of each board is in a vertical direction, the thickness and length being in horizontal directions. 85

Any well-known means of heating the air and the vapor in the kiln may be used in conjunction with this invention. When steam pipes are used they may be arranged beneath the lumber piles at the sides of the kiln or in any other convenient manner. Any convenient form and arrangement of 90 heaters may be used.

The drawings show and the specification 95 describes steam jet pipes for increasing the humidity, and air inlet flues and air outlet flues with suitable dampers for decreasing the humidity.

While the drawings show and the specification 100 describes specific means for heating the air and the vapor in the kiln and for regulating the humidity of the air in the kiln, this invention is not limited specifically to the arrangements described, but may

make use of any other well-known and suitable means for accomplishing the same purposes. While the drawings illustrate and the specification describes certain specific forms of piling, the invention is not limited to these particular forms since it is equally applicable to other forms; neither is the invention limited to the specific form of rails, trucks, and track supports illustrated in the drawings and described in the specification.

Referring to Figures 1, 2, and 3, which are correspondingly lettered: AA represent the vertical fan housings. These housings serve to prevent the circulation from bypassing the fans. BB are the fans producing the circulation. Straight-bladed disk fans are preferable. Any type of fan, however, in which the reversal of the direction of rotation of the fan produces a reversal in the direction of the flow of the air current passing through the fan can be used. The two fans on each shaft are of opposite pitch so that when the shaft is rotated the two fans blow either towards each other or away from each other. CC are the shafts upon which the fans are mounted. Provision is made to take care of the expansion and contraction of these shafts with changes in the temperature in the kiln and to take care of the thrust of the fans. This provision consists in equipping one of the bearings II with suitable thrust rings or collars and equipping all of the other bearing II on each shaft with any well-known means for longitudinal motion. Plain bearings and roller bearings require no special provision of this kind. Certain types of ball bearings require housings which permit the entire bearings to slide longitudinally within them. DD are the air inlet dampers used to regulate and control the amount of air entering the kiln from the outside. EE are the heating coils. These may be of the return bend type or other convenient type. FF are the steam jet pipes used to increase the humidity of the air in the kiln. Suitable openings are provided to permit the escape of the steam throughout the length of the kiln. Various other common and well-known arrangements may be used. GG are the lumber-supporting trucks. HH are the shaft hangers. II are bearings for the shafts CC. JJ are the tracks upon which the lumber-supporting trucks run. KK are the side walls of the kiln. LL is the lumber to be dried. MM are the track supports. OO are air outlet dampers for controlling the amount of air being exhausted from the kiln. RR are the motors which furnish the power to drive the fans. SS are switches for controlling the speed and rotation of the motor armature. The motors RR are direct-connected to their respective shafts. While the drawings show and the specification describes electric motors, any other suitable driving means may

be used. TT are air inlet flues in which the dampers DD are fitted. UU are the air outlet flues in which the dampers OO are fitted. WW are the side air passages between the piles of lumber and the side walls of the kiln. XX are the main air distributors. YY are the second diffusers. Z is the first diffuser. The plenum chamber between the second diffusers and the first diffuser is the secondary plenum chamber. While the drawings show and the specification describes certain specific arrangement of the fans and shafts, this invention is not limited to this particular arrangement, since it is obvious that its functions can be performed in an equivalent manner with other arrangements of the fans.

The operation of the kiln is briefly as follows: The lumber is placed in the kiln, the doors and all of the dampers are closed, and the kiln is started. Steam is turned into the coils and the steam jets are turned on. Suitable regulating devices are provided to control and regulate the supply of steam to the heating coils and the supply of the steam to the steam jets. If it is found impossible to reduce the humidity to the desired point with the steam jets all turned off, the dampers DD and OO are opened to allow fresh air to enter and moist air to escape. These dampers should be adjusted so that a humidity below that desired will be secured. The steam jets may then supply a sufficient amount of steam to bring the humidity up to the desired point. Assuming that the direction of rotation of the fans is such that the air and vapor move upward through the lumber piles LL they will pass downward through the side air passages WW, through the fans BB, over the heating coils EE, through the first diffuser Z, through the second diffusers YY, and then upward through the lumber again. When the direction of rotation of the fans is reversed the direction of the circulation of air and vapor is likewise reversed. When the direction of the air circulation is upward through the lumber piles LL the plenum chamber in which the heating coils EE are located and the secondary plenum chamber between the diffusers YY and Z will be under slight pressure. When the circulation is reversed they will be under a slight vacuum. Furthermore, the side passages WW will be under slight pressure. The length of these passages tends to even out the air flow and avoids the necessity for diffusers and plenum chambers between the fans and the lumber. Greater uniformity in air flow might be secured by the addition of other sets of plenum chambers and diffusers. The principle of operation would, however, still remain the same and expediency would determine how many diffusers would be necessary.

It has been found through experience

with a great many different types of forced circulation in dry kilns that it is not possible to secure uniformity of distribution of the air and vapor if they be handled at high velocities. In order to produce uniform satisfactory circulation, it is essential that the air and vapor be moved at low velocities and that special means be provided for the uniform distribution of the air and vapor through the kiln. The use of internal fans and large plenum chambers produces this result, since the velocity of the air and vapor through the fans themselves is comparatively low and the velocity in the plenum chambers is so small that the velocity head can not be measured with manometers and similar instruments usually used for the purpose.

It is well understood that when the circulation of the air and the vapor in the kiln is continuously in one direction, that portion of the pile at which the air enters will dry more rapidly than the opposite side since the air in its passage through the lumber picks up moisture and thus reduces its drying capacity. The reversal of the direction of the air circulation overcomes this defect since that edge of each lumber pile which was the entering air edge before reversal becomes the leaving air edge after reversal. Those portions of the piles which dried fastest before reversal dry most slowly after reversal. The reversal of the circulation will in practice be done periodically every two or three days or oftener, the exact period being determined by the condition of the lumber in the kiln.

Several arrangements of the plenum chambers are possible and practicable. The principal object of the plenum chambers and diffusers is to produce a uniform flow of air and vapor through the lumber to be dried, and any detailed arrangement which will accomplish this result will be satisfactory if at the same time it does not consume an excessive amount of power.

Having fully described the principles of

this invention and the manner in which they can be embodied in a dry kiln, I claim as original:

1. In a double track dry kiln arranged for edge stacking: a series of cross shafts; means for rotating said shafts in either direction to cause reversal of the circulation of the air and vapor in said kiln; two fans of opposite pitch mounted for rotation on each shaft; and an air distributing system comprising a main air distributor and two sets of diffusers.

2. In a double track dry kiln arranged for edge stacking: a series of cross shafts; means for rotating said shafts in either direction to cause reversal of the circulation of the air and vapor in said kiln; dampered air inlet flues and dampered air outlet flues; two fans of opposite pitch mounted for rotation on each shaft; and an air distributing system comprising a main air distributor and two sets of diffusers.

3. In a double track dry kiln arranged for edge stacking: a series of cross shafts; means for rotating said shafts in either direction to cause reversal of the circulation of the air and vapor in said kiln; dampered air inlet flues and dampered air outlet flues; means for heating the kiln and its contents; two fans of opposite pitch mounted for rotation on each shaft; and an air distributing system comprising a main air distributor and two sets of diffusers.

4. In a double track dry kiln arranged for edge stacking: a series of cross shafts; means for rotating said shafts in either direction to cause reversal of the circulation of the air and vapor in said kiln; dampered air inlet flues and dampered air outlet flues; means for heating the kiln and its contents; means for humidifying the atmosphere in the kiln; two fans of opposite pitch mounted for rotation on each shaft; and an air distributing system comprising a main air distributor and two sets of diffusers.

February 18, 1925.

ROLF THELEN.
